DESIGN FOR A LADY'S COLLAR

Nathan Appelbaum, New York, and Sarah Shron, Brooklyn, N. Y.

Application March 18, 1936, Serial No. 61,678

Term of patent 3½ years

To all whom it may concern:

Be it known that we, Nathan Appelbaum, a citizen of Poland, and Sarah Shron, a citizen of the United States, the former residing at New York, in the county of Bronx and State of New York, and the latter at Brooklyn, in the county of Kings and State of New York, have invented a new, original, and ornamental Design for a Lady's Collar, of which the following is a specification, reference being had to the accompanying drawing, forming part thereof. The collar is made of colored patent leather.

In the drawing:

Fig. 1 is a plan view of a lady's collar, showing our new design.

Fig. 2 is an edge view thereof.

We claim:

The ornamental design for a lady's collar, as shown and described.

NATHAN APPELBAUM.
SARAH SHRON.
